UNITED STATES PATENT OFFICE.

ALFRED MARKOWSKY, OF WOODBRIDGE, NEW JERSEY.

DISINFECTANT HOLDER FOR URINALS AND WATER CLOSETS.

1,411,218.

Specification of Letters Patent. Patented Mar. 28, 1922.

Application filed February 13, 1920. Serial No. 358,544.

To all whom it may concern:

Be it known that I, ALFRED MARKOWSKY, citizen of the United States, residing at Woodbridge, in the county of Middlesex and State of New Jersey, have invented certain new and useful Improvements in Disinfectant Holders for Urinals and Water Closets, of which the following is a specification.

10 This invention relates to disinfectant holders for water closets and urinals, and belongs particularly with that class or type of containers for small disinfectant bodies that are held by the containers in the path 15 of the flushing water. Certain containers of this character with which this applicant is acquainted, are tubular bodies of a foot or two in length, and are made of resilient material or provided with auxiliary, longitudinal springs affording the necessary 20 elasticity to maintain the holders in place against the inner wall of the closet or urinal and in the path of the flushing water. It is with this especial type that this invention 25 is most directly concerned.

The object of this invention is to produce a holder for disinfectants or the like, wherein the parts are of special construction and arrangement believed to materially cheapen 30 the cost of manufacturing and assembling the parts, and to add much to the convenience and ease with which the holder may be applied to a closet or urinal.

In the accompanying drawings the particular construction and arrangement or combination of the parts of this invention are illustrated. Fig. 1 is a front view of a holder constructed in accordance with this invention. Fig. 2 is a rear view of the same. 40 Fig. 3 is a cross-section on the broken line 3-3 of Fig. 1. Fig. 4 is a horizontal section of a urinal showing this invention applied thereto. Fig. 5 shows a modified holder.

45 Throughout the description and drawings the same letter is used to refer to the same part.

Considering the drawings, A is a tubular holder, having the openings *a* through which 50 flushing water may pass. The holder or container shown is formed of flat teeth B joined together to form annular parts as best shown in Fig. 3, but it is not intended to confine this invention to that single construction, as a spiral coil holder either of

round or of flat wire could be obviously substituted. The holder carries the disinfectant or deodorant globules *b* which are washed away by the repeated flushings of the urinal or closet. 60

On the rear of the holder A will be noted a longitudinal rib C, and the ends of this enlargement extend beyond the ends of the holder proper and are marked D and *d*. This rib C and its end extensions are in 65 practice formed integrally with and of the same resilient material as is employed to make the holder itself. The rib C and extensions constitute the spring by which the holder is held in place in the receptacle, for 70 example, in the urinal E, shown in Fig. 4, and it will be noted in this figure that the wall of the urinal is provided with the shoulders *e*, that are engaged by the ends of the spring extensions D and *d*. The urinal 75 is provided with inlets for flushing water, such as the inlets F.

In the operation of this invention, the holder is filled with the globules *b*, and then it is bent or bowed until it may be introduced 80 into the urinal, or other receptacle, the ends of the spring marked D and *d* which extend beyond the holder engage the wall of the receptacle frictionally, or, as illustrated, the ends of the spring may engage the shoulders 85 *e* or like projections. Now, the tendency of the spring, and of the bowed resilient holder itself is to straighten out, and such effort maintains the holder in place against the wall of the receptacle and in the path of the 90 flushing water. The desired result in the operation of this invention is that the holder throughout its entire length may be closely held in contact with the wall of the receptacle, in order that the flushing water may all 95 pass either through or over the holder and in contact as much as may be with the disinfectant globules *b*.

It is considered to be within the purview of this invention to fashion the same of any 100 material, either celluloid or metal, and it is clear that the spring C and its extending ends may be reenforced, or its resilience increased or diminished by suitably altering its thickness or the material of which it is 105 composed.

The modification illustrated in Fig. 5 consists only in a change of form for the ends of the spring member. The holder G is the same as before. It has the spring end *g* ex- 110

tending beyond the end of the holder and provided with a hooked termination H arranged to engage the shoulder of the urinal.

Having now described this invention, and explained the mode of its operation, what I claim is:—

1. In a device of the character described, the combination with a holder having openings through which water may pass, the said holder being formed of resilient material, of a receptacle provided with flushing water inlets, springs extending beyond the ends of the said holder and connected therewith and arranged to engage the wall of the receptacle to maintain the holder in place against the wall in the path of the flushing water.

2. In a device of the character described, the combination with a holder having openings through which water may pass, the said holder being formed of resilient material, of a receptacle provided with flushing water inlets, springs extending beyond the ends of the holder and arranged to engage the wall of said receptacle to maintain the holder in place against said wall in the path of the flushing water, the said springs being formed integrally with the said holder and being linear extensions thereof.

3. In a device of the character described, the combination with a tubular holder having openings through which water may pass, the said holder being formed of bendable material, of a receptacle provided with flushing water inlets, springs extending beyond the ends of the holder and connected therewith and arranged to engage the wall of the said receptacle to maintain the said

holder in place against the said wall in path of the flushing water.

4. In a device of the character described, the combination with a tubular holder having openings through which water may pass, the said holder being formed of resilient material, of a receptacle provided with flushing water inlets, linear springs extending beyond the ends of the holder and formed integrally with and of the same material as the holder and arranged to engage the wall of the said receptacle and to maintain the said holder against the said wall in the path of the flushing water.

5. In a device of the character described, the combination with a tubular holder having openings through which water may pass, the said holder being formed of resilient material, of a receptacle provided with flushing water inlets and having shoulders at the sides, linear springs extending beyond the ends of the holder, the ends of the said springs arranged to engage said shoulders of the said receptacle and to maintain the said holder in place against the said wall in the path of the flushing water.

6. A disinfecting device comprising an elongated resilient member formed to lie within the recess beneath the inwardly extending rim of a bowl and to hold disinfecting material in the path of the water flowing from the rim, and strut members carried by the ends of the resilient member and formed to abut against the rear of the bowl to hold the forward portion of the tube against the forward part of the bowl.

In testimony whereof I affix my signature.

ALFRED MARKOWSKY.
